UNITED STATES PATENT OFFICE

DANIEL DAVID PALMER, OF DAVENPORT, IOWA

DESIGN FOR A SIGN

Application filed January 8, 1931. Serial No. 38,237. Term of patent 14 years.

To all whom it may concern:

Be it known that I, DANIEL DAVID PALMER, a citizen of the United States of America, residing at Davenport, in the county of Scott and State of Iowa, have invented a new, original, and ornamental Design for Signs, of which the following is a specification, reference being had to the accompanying drawing, forming part hereof.

The figure is a perspective view of a sign, showing my new design.

I claim:

The ornamental design for a sign as shown.

Signed at Davenport, in the county of Scott and State of Iowa, this 5 day of January, 1931.

DANIEL DAVID PALMER.
